UNITED STATES PATENT OFFICE.

CECIL R. MARTIN, OF STERLING, ILLINOIS, ASSIGNEE TO FRANTZ MANUFACTURING CO., OF STERLING, ILLINOIS, A CORPORATION OF ILLINOIS.

DOOR-HANGER TRACK AND HOUSING.

1,380,668.

Specification of Letters Patent. Patented June 7, 1921.

Application filed June 20, 1918. Serial No. 241,045.

To all whom it may concern:

Be it known that I, CECIL R. MARTIN, a citizen of the United States of America, and resident of Sterling, Illinois, have invented a certain new and useful Improvement in Door-Hanger Tracks and Housings, of which the following is a specification.

This invention relates to sliding door hanger tracks of that kind in which the track is supported by the housing which incloses the hangers, and in which the housing is made in sections, whereby the track and housing can be of any suitable or desired length.

The object of the invention is to provide an improved construction and arrangement whereby the track is integral with the housing, being formed from the sheet metal from which the housing is constructed, so that the lap joints between the sections of the housing support the weight of the door directly on the housing, as will hereafter more fully appear.

It is also an object to provide certain details and features of construction and combinations tending to increase the general efficiency and desirability of a sectional door hanger track and housing of this particular character.

To the foregoing and other useful ends the invention consists in matters hereinafter set forth and claimed, and shown in the accompanying drawings, in which—

Figure 1 is a front elevation of a sliding door mounted on a sectional track and housing embodying the principles of the invention.

Fig. 2 is an enlarged vertical section on line 2—2 in Fig. 1.

Fig. 3 is an enlarged vertical section on line 3—3 in Fig. 1.

Fig. 4 is a perspective of one of the combined track and housing sections.

Fig. 5 is an enlarged detail section on line 5—5 in Fig. 2.

As thus illustrated, the sliding door 1 is disposed in front of the doorway of the building 2 in the usual and well known manner, and provided with hangers 3 of any suitable, known, or approved character.

The sectional track and housing is composed of a plurality of sections of the kind shown in Fig. 4, each section comprising an upper vertical web 4, an inclined web 5 integrally united to the lower edge of said

vertical web, an outer web or bulging wall 6, and a lower trough-shaped portion 7, these walls and portions being all integrally formed from one piece of sheet metal, such as sheet steel, pressed or otherwise given the proper shape. At one end, each track and housing section is displaced outwardly to form an overlapping portion 8, which is in shape exactly like the body of the track and housing section, but a little larger, whereby this overlapping portion is adapted to receive the straight end portion of another section, so that the inner surface of the entire combined track and housing is flush and smooth, notwithstanding the lap joints 70 which are thus provided between the telescoping end portions of the sections. Each end of the vertical web 4 is provided with holes 9 and in this way each lap joint is provided with two holes which register 75 at the upper end of the joint, and bolts 10 are inserted through these holes to secure the track and housing structure to the building. The trough-shaped portions 7 form a channel or gutter which serves as 80 a track for the wheels of the door hangers 3, whereby the hangers travel between the track and the building. The lap joints formed by the telescoping end portions of the track and housing sections sustain the 85 weight of the door, and, in addition, the wheels of the door hangers travel on a track which is formed integral with the sheet metal housing, and which is, with the construction shown and described, practically 90 a part of the housing itself. With the track and housing sections thus fitted together, and taking into account that the portions 7 and their inner edges 11 bend upward a distance, so that each overlapping portion 8 95 curves upwardly around the end of the next section, it is obvious that the sections cannot be relatively displaced at their ends. The sections are held together at their upper edges by the bolts 10, and at their lower 100 edges by the semi-tubular formation of the sections themselves, so that the different sections of the track formed by the portions 7 cannot get out of alinement, and provide a smooth and flush surface over which the 105 wheels of the door hangers travel when the door is opened and closed.

Preferably, the upper web 4 of each section is provided with a groove or longitudinal distortion 12, the groove being on the 110

inner surface and the bulge being on the outer surface of the sheet metal, whereby the webs or vertical walls 4 are rendered sufficiently stiff for the purpose of rigidly supporting the track and housing in position on the building.

With the foregoing construction, it will be seen that no brackets or hangers are necessary for the track and housing, inasmuch as 10 the lap joints provide integral connections between the sections and stiffen the housing sufficiently to prevent sagging thereof under the weight of the door. In other words, the displaced portions 8 not only enable the sections to telescope at their ends, one within the other, but also render the combined track and housing structure more rigid. While the lap joints support the weight of the door, it is also true that the track is integral 20 with the housing sections, and is formed from the sheet metal of the housing itself, so that the invention not only obviates the necessity of using brackets or hangers for coupling together and supporting the ends 25 of the sections, but also obviates the necessity of using either a separately formed or separately mounted track of any kind, the gutter-shaped bottom portions of the housing sections themselves serving as the track 30 for the wheels of the hangers. It will be understood, of course, that the combined track and housing sections can be of any suitable or desired length, and that for some purposes, and under certain conditions, one 35 section of the desired or proper length will be sufficient. In other cases, however, a plurality of sections will be combined to form a track and housing of the desired length. The outwardly displaced or offset portion 8 40 may be of any suitable or desired length, depending on the length desired for the overlap, or the size of the lap joints, the weight of the door, and other things. In any case, however, the sheet metal at this point is 45 preferably displaced or offset to an extent exactly the thickness of the sheet metal itself, so that the shoulder 13, where the offset terminates, will engage the end of the next section, and will be in exact alinement 50 therewith, whereby the entire inner surface of the housing will be flush and smooth. Also, the track 7 can be of any suitable or desired formation, but is preferably channel-shaped to make the track stiff and strong 55 and capable of sustaining the weight of the door, and to keep the wheels of the hangers from getting off the track. Also, it will be seen that the end of one track section 7 overlaps the other, to form the sectional track, 60 and that these lap joints between the track sections are not fastened together, but simply depend upon the bolts 10 and the general stiffness and rigidity of the housing sections to hold the ends of the track sections 65 in alinement to provide a smooth path of

travel for the wheels of the hangers. In cross section the combined track and housing is semi-tubular, being open at its inner side, and is of oval formation, so that it presents the appearance of a flattened tube having its 70 inner side wall displaced and turned up to form the attaching web 4 previously described. But the short curve of the track portions 7 merges into the longer curve of the outer wall 6, and the top is curved at 14 75 between this wall and the inclined wall 5, so that the oval is complete, practically, except for the inner side thereof, and this formation insures the requisite strength and stiffness for the housing under the weight of the 80 door.

The holes 9, it will be seen, form provisions in the double thickness of the upper portion of each lap joint for attaching the sectional housing and track to the building. 85 Moreover, each lap joint extends from the horizontal upper edge of the structure to the inner edge of the track, so that relative displacement between the telescoped ends of the sections, in any direction, is prevented by 90 the lap joints themselves, and without the insertion of any rivets or bolts or other fastening devices, with the single exception of the bolts 10 by which the sections are secured to the building, and by which the 95 sections are connected together.

What I claim as my invention is:—

1. In a door hanger track and housing structure for supporting sliding doors, a plurality of sheet metal housing sections, a sectional track on said housing sections, integral therewith, so that each entire track and housing section is formed from a single piece of sheet metal, and a door hanger traveling on and supported entirely by said track, the ends of said sections being lapped one upon the other and secured together, thereby to provide a lap-joint between adjacent sections, and to stiffen the housing against sagging under the weight of the door, so that the housing sections are in themselves sufficient to support said track, the lap-joint thus formed by the integral ends of the sections having provisions at the upper end thereof for securing the housing to a building, and the tread of said track being formed in cross section to both stiffen the structure and prevent lateral displacement of the hanger therefrom.

2. In a device of the class set forth, a combined housing and track to inclose and support the hangers of a door, consisting of sheet metal sections secured together and bent longitudinally into the desired shape necessary to support the entire weight of the door and having transverse integral reinforcing members provided at intervals along the length thereof to support the housing and track, the track being integral with the housing, so that each entire track and housing sec-

tion is formed from a single piece of sheet metal, these integral members following the cross sectional shape of the sheet metal sections and providing the stiffness necessary for supporting the door, and the tread of said track being formed in cross section to both stiffen the structure and prevent lateral displacement of the hanger therefrom.

3. A structure as specified in claim 1, the 10 end of one track section overlapping the end of another track section, so that said lap joint is continuous from the upper edge of the housing to the inner edge of the track.

4. A structure as specified in claim 1, said 15 track being shaped to form a gutter in which the hanger travels, so that the end of one track section rests in the end of the other track section, and whereby one entire section telescopes within the end of the other section, so that the track sections are held 20 against lateral relative displacement.

5. A structure as specified in claim 2, said 25 members extending continuously from the upper edge of the housing to the inner edge of the track.

6. In a sheet metal door hanger track and housing, an upper flange for attachment to

the building, an inclined top wall extending outwardly from the lower edge of said flange, a curved side wall supported by the 30 top wall, forming a wide and shallow trough shaped front wall, so that the front of the housing is outwardly convex and inwardly concave, a curved bottom forming a narrow trough shaped track, and integral means at 35 intervals in the track and housing to stiffen the sheet metal, the combined track and housing thus formed of sheet metal being oval in form when viewed in cross section, with the inner side of the oval left open and 40 omitted below said flange, in combination with a hanger having a wheel supported and held by said track against lateral displacement, and with the shallow inner trough of the front wall forming clearance for the 45 side of the hanger, in which the said track and housing are formed of sheet metal sections, with the end of one section telescoped within the end of another section, and with integrallapping end portions to sustain the 50 weight of the door.

Signed by me at Sterling, Illinois, this 20th day of May, 1918.

CECIL R. MARTIN.
